CIRCUIT BREAKER

William H. Frank and Elwood T. Platz,
Detroit, Mich.Original application February 21, 1940, Serial No.
320,116. Divided and this application September
30, 1940, Serial No. 358,944

18 Claims. (Cl. 200—116)

This application relates to manually operable switches or circuit breakers.

The object of this invention is to produce a circuit breaker of the type disclosed in our prior application, Serial No. 320,116, filed February 21, 1940, of which the instant application is a division. This invention is an improvement over the circuit breaker disclosed in the said prior application in that it employs a simpler construction which has many manufacturing economies and advantages, and, further, it permits a more compact circuit breaker than is that of the subject prior application.

For an understanding of the breaker hereof, reference should be had to the appended drawings in which—

Figs. 1 to 3 show the switch parts in closed circuit, open circuit, and overload released positions, respectively.

Referring to the drawing, it will be seen that it shows a handle 40 pivoted at 41 to a casting and connected at 42 to one end of a bowed leaf spring 43 whose other end is connected at 44 to an arm 45 pivotally mounted at 45a on the casing and having a slot 45b for receiving the end of a circuit responsive bimetal latch 46 connected through flexible connection 47 to a movable contact 48 suitably mounted on the spring 43 with the movable contact mating with a stationary contact 50 for butt contact. The handle is formed with a large recess in its under side to receive arm 45 and other parts of the breaker.

When the handle is in the closed circuit position of Fig. 1, the spring 43 is stressed lengthwise; one end is held by the engagement of the spring with arm 45 and by the engagement of that arm with latch 46. The other end of the spring is held at the handle connection 42 by the reaction of the contact pressure of butt contacts 48—50. The stress on spring 43 results in contact pressure at 48—50, and also biases arm 45 to move counterclockwise.

When the handle is moved to the open circuit position (Fig. 2) the spring is stressed and moves, lifting the contact 48 from the contact 50 with the final part of such movement of contact 48 being a snap movement, the latch connection end of the spring being held by the arm and the latch. In open circuit position, also, the spring 43 is stressed lengthwise.

On circuit closing operation movement of the handle from the open circuit position, Fig. 2, to the closed circuit position, Fig. 1, will cause contact 48 to engage contact 50 with a snap action.

When the latch releases due to overload, arm 45, biased by spring 43 counterclockwise, is released by the latch whereupon the spring 43 and arm 45 will snap counterclockwise about end 43 as a pivot with a snap action, lifting the contact 48 off the contact 50.

During movement of handle 40 to and from the positions of Figs. 1-2, spring 43 is stressed lengthwise an additional amount, over and above the lengthwise stress thereon when the parts are stationary, due to the difference in curvature of the arc "A" swung on center 41 with radius 41—42 and the arc "B" swung on center 44 with radius 44—42. Such additional stress is relieved as the line 44—42 crosses center 41, to produce snap action.

For resetting the handle moves towards the open circuit position (Fig. 2) so that the right end of the handle pushes arm 45 down to the tip of latch 46 which has been cooled and returned and to re-engage the latch tip with the slot 45b of the arm.

During reset contact 48 does not pass through circuit closed position since as the latch connection end of spring 43 moves down, the other end 42 moves up.

The spring 43 provides contact pressure when the circuit is closed, biases the contacts separated when the latch releases or when the handle is moved to the open circuit position, biases the contact into closed circuit position when the handle is moved to closed circuit position, and gives a snap action to the final part of each movement of the contact when the contact is moved by the handle. The contacts are of the butt contact pressure type and the spring establishes butt contact pressure.

The provision of the arm 45 reduces the friction between the moving spring and the stationary parts, on overload, due to the fact that the pivoted arm support for the latch end of the spring gives a more frictionless support for the spring than would be provided if the latch connection end of the spring were formed with a cross piece to slide in a slot, as in the case of the circuit breaker of the parent application, Figs. 1 to 3 of Serial No. 320,116.

Resetting of the breaker hereof is facilitated because it is easier to swing the latch end of the spring 43 and arm 45 downwardly to the latch than it is to slide the latch end of the spring down in casing slots, as in the case of the breaker of Figs. 1 to 3 of Serial No. 320,116.

Now having described the device herein shown, reference will be had to the claims which follow.

for a determination of the protection sought herein.

We claim:

1. A manually operable switch and circuit breaker including a bowed leaf spring, a contact thereon and moved thereby, a handle directly connected to one end of the spring so as to provide for manipulation thereof, a pivotally mounted arm to which the other end of the spring is directly connected, a circuit current responsive latch directly and releasably connected to said arm at a point adjacent the connection of the spring to said arm, the arm providing a releasable connection between the latch and the adjacent end of the spring, the handle and the latch providing direct connected separate holding means for the spring, the relation between the spring, the latch, and the handle being such that on release of the latch the spring biases the contact to open circuit position by moving around the handle connection thereto as a pivot without requiring movement of the handle, and on movement of the handle the spring moves the contact to open circuit position by moving around the latch connection thereto as a pivot without moving the latch, the points of connection between the handle and spring and between the latch and spring being spaced from each other, the spring normally biasing the contact into closed circuit position.

2. A manually operable switch and circuit breaker including a bowed leaf spring, a contact thereon and moved thereby, a handle directly connected to one end of the spring so as to provide for manipulation thereof, a pivotally mounted arm to which the other end of the spring is directly connected, a circuit current responsive latch directly and releasably connected to said arm at a point adjacent the connection of the spring to said arm, the arm providing a releasable connection between the latch and the adjacent end of the spring, the handle and the latch providing direct connected separate holding means for the spring, the relation between the spring, the latch, and the handle being such that on release of the latch the spring biases the contact to open circuit position by moving around the handle connection thereto as a pivot without requiring movement of the handle, and on movement of the handle the spring moves the contact to open circuit position by moving around the latch connection thereto as a pivot without moving the latch, the points of connection between the handle and spring and between the latch and spring being spaced from each other, the spring normally biasing the contact into closed circuit position, the handle being pivotally mounted and the spring being arranged to move with a snap action when the handle moves the spring to give snap action to the final parts of the handle actuated movements of the contact.

3. A manually operable switch and circuit breaker including a bowed leaf spring, a contact thereon and moved thereby, a handle and a circuit condition responsive latch, the spring connecting the handle and the latch and for this purpose having its ends connected directly to the handle and the latch, the latch-spring connection being releasable on latch movement due to circuit abnormality so that the spring moves the contact to open circuit position, the handle being actuatable to move the spring, and thus the contact, to and from open and closed circuit positions, there being a pivotally mounted arm in

the breaker to which the latch connection end of the spring is connected and to which the latch is releasably connected, both connections to the arm being adjacent, such arm providing the releasable connection between the latch and the spring.

4. A manually operable switch and circuit breaker including a bowed leaf spring, a contact thereon and moved thereby, a handle, and a circuit condition responsive latch, the spring connecting the handle and the latch and for this purpose having its ends connected directly to the

handle and the latch, the latch-spring connection being releasable on latch movement due to 15 circuit abnormality so that the spring moves the latch to the open position.

contact to open circuit position, the handle being actuatable to move the spring, and thus the contact, to and from open and closed circuit posi-

20 tions, there being a pivotally mounted arm in the breaker to which the latch connection end of the spring is connected and to which the latch

is releasably connected, both connections to the arm being adjacent, such arm providing the releasable connection between the latch and the

25 spring, the spring, in closed circuit position of the parts, biasing the contact to such closed position for establishing contact pressure and also

30 biasing the contact in such a direction that the contact will move to open circuit position in the event of latch release with movement of the han-

idle from open circuit position to closed circuit position moving the spring to a position wherein it biases the contact to closed circuit position with contact pressure.

35 5. A manually operable switch and circuit breaker including a bowed leaf spring, a contact thereon and moved thereby a handle and a cir-

thereon and moved thereby, a handle, and a circuit condition responsive latch, the spring connecting the handle and the latch and for this purpose having its ends connected directly to the handle and the latch, the latch-spring connection

handle and the latch, the latch-spring connection being releasable on latch movement due to circuit abnormality so that the spring moves the contact to open circuit position, the handle being

45 contact to open circuit position, the handle being actuatable to move the spring, and thus the contact, to and from open and closed circuit positions, there being a pivotally mounted arm in

tions, there being a pivotally mounted arm in the breaker to which the latch connection end of the spring is connected and to which the latch is releasably connected, both connections to the

50 is releasably connected, both connections to the arm being adjacent, such arm providing the releasable connection between the latch and the spring, the handle being pivotally mounted and

55 spring, the handle being pivotally mounted and the spring being arranged to move with a snap action on handle actuated movement of the spring whereby the final part of each handle

spring whereby the final part of each handle actuated movement of the spring and contact is a snap movement.

6. A manually operable switch and circuit breaker including a bowed leaf spring, a contact thereon and moved thereby, a handle, and a cir-

cuit condition responsive latch, the spring connecting the handle and the latch and for this purpose having its ends connected directly to

65 the handle and the latch, the latch-spring connection being releasable on latch movement due to circuit abnormality so that the spring moves

70 to circuit abnormality so that the spring moves the contact to open circuit position, the handle being actuatable to move the spring, and thus the contact to and from open and closed circuit

contact, to and from open and closed circuit positions, there being a pivotally mounted arm in the breaker to which the latch connection end of the conductive member is attached.

of the spring is connected and to which the latch 75 is releasably connected, both connections to the

arm being adjacent, such arm providing the releasable connection between the latch and the spring, the spring, in closed circuit position of the parts, biasing the contact to such closed position for establishing contact pressure and also biasing the contact in such a direction that the contact will move to open circuit position in the event of latch release, with movement of the handle from open circuit position to closed circuit position moving the spring to a position wherein it biases the contact to closed circuit position with contact pressure, the handle being pivotally mounted and the spring being arranged to move with a snap action on handle actuated movement of the spring whereby the final part of each handle actuated movement of the spring and contact is a snap movement.

7. A manually operable switch and circuit breaker including a spring, a contact moved thereby, a handle directly connected to one end of the spring so as to provide for manipulation thereof, a pivotally mounted arm to which the other end of the spring is directly connected, a circuit current responsive latch directly and releasably connected to said arm at a point adjacent the connection of the spring to said arm, the arm providing a releasable connection between the latch and the adjacent end of the spring, the handle and the latch providing direct connected separate holding means for the spring, the relation between the spring, the latch, and the handle being such that on release of the latch the spring biases the contact to open circuit position by moving around the handle connection thereto as a pivot without requiring movement of the handle, and on movement of the handle the spring moves the contact to open circuit position by moving around the latch connection thereto as a pivot without moving the latch, the points of connection between the handle and spring and between the latch and spring being spaced from each other, the spring normally biasing the contact into closed circuit position, the spring comprising a bowed leaf spring between the latch and the handle, and on which the movable contact is supported.

8. A manually operable switch and circuit breaker including a spring, a contact operatively connected thereto so as to be moved thereby, a handle directly connected to the spring so as to provide for manipulation thereof, a circuit current responsive latch directly connected to said spring, the handle and the latch providing direct connected separated holding means for the spring, the relation between the spring, the latch, and the handle being such that on release of the latch the spring biases the contact to open circuit position by moving around the handle connection thereto as a pivot without requiring movement of the handle, and on movement of the handle the spring moves the contact to open circuit position by moving around the latch connection thereto as a pivot without moving the latch, the points of connection between the handle and spring and between the latch and spring being spaced from each other, the spring normally biasing the contact into closed circuit position, the handle being pivotally mounted and the spring being arranged to cross the pivot of the handle when the handle moves the spring to give snap action to the final parts of the handle actuated movements of the contact, the spring comprising a bowed leaf spring between the latch and the handle, and on which the movable contact is supported, there being a pivotally mounted arm

5 in the breaker to which the latch connection end of the spring is connected and to which the latch is releasably connected, both connections to the arm being adjacent, such arm providing the releasable connection between the latch and the spring.

9. A manually operable switch and circuit breaker including a spring, a contact operatively connected thereto so as to be moved thereby, a handle, and a circuit condition responsive latch, the spring connecting the handle and the latch and for this purpose having its ends connected directly to the handle and the latch, the latch-spring connection being releasable on latch movement due to circuit abnormality so that the spring moves the contact to open circuit position, the handle being actuatable to move the spring, and thus the contact, to and from open and closed circuit positions, there being a pivotally mounted arm in the breaker to which the latch connection end of the spring is connected and to which the latch is releasably connected, both connections to the arm being adjacent, such arm providing the releasable connection between the latch and the spring, the spring comprising a bowed leaf spring between the latch and the handle, and on which the movable contact is supported.

10. A manually operable switch and circuit breaker including a spring, a contact operatively connected thereto so as to be moved thereby, a handle, and a circuit condition responsive latch, the spring connecting the handle and the latch and for this purpose having its ends connected directly to the handle and the latch, the latch-spring connection being releasable on latch movement due to circuit abnormality so that the spring moves the contact to open circuit position, the handle being actuatable to move the spring, and thus the contact, to and from open and closed circuit positions, there being a pivotally mounted arm in the breaker to which the latch connection end of the spring is connected and to which the latch is releasably connected, both connections to the arm being adjacent, such arm providing the releasable connection between the latch and the spring, the spring comprising a bowed leaf spring between the latch and the handle, and on which the movable contact is supported.

11. A manually operable switch and circuit breaker including a spring, a contact operatively connected thereto so as to be moved thereby, a handle, and a circuit condition responsive latch, the spring connecting the handle and the latch and for this purpose having its ends connected directly to the handle and the latch, the latch-spring connection being releasable on latch movement due to circuit abnormality so that the spring moves the contact to open circuit position, the handle being actuatable to move the spring, and thus the contact, to and from open and closed circuit positions, there being a pivotally mounted arm in the breaker to which the latch connection end of the spring is connected and to which the latch is releasably connected, both connec-

tions to the arm being adjacent, such arm providing the releasable connection between the latch and the spring, the handle being pivotally mounted and the spring being arranged to cross the handle pivot on handle actuated movement of the spring whereby the final part of each handle actuated movement of the spring and contact is snap movement, the spring comprising a bowed leaf spring between the latch and the handle, and on which the movable contact is supported.

12. A manually operable switch and circuit breaker including a spring, a contact operatively connected thereto so as to be moved thereby, a handle, and a circuit condition responsive latch, the spring connecting the handle and the latch and for this purpose having its ends connected directly to the handle and the latch, the latch-spring connection being releasable on latch movement due to circuit abnormality so that the spring moves the contact to open circuit position, the handle being actuatable to move the spring, and thus the contact, to and from open and closed circuit positions, the spring, in closed circuit position of the parts, biasing the contact to such closed position for establishing contact pressure and also biasing the contact in such a direction that the contact will move to open circuit position in the event of latch release, with movement of the handle from open circuit position to closed circuit position moving the spring to a position wherein it biases the contact to closed circuit position with contact pressure, the handle being pivotally mounted and the spring being arranged to cross the handle pivot on handle actuated movement of the spring whereby the final part of each handle actuated movement of the spring and contact is a snap movement, the spring comprising a bowed leaf spring between the latch and the handle, and on which the movable contact is supported, there being a pivotally mounted arm in the breaker to which the latch connection end of the spring is connected and to which the latch is releasably connected, both connections to the arm being adjacent, such arm providing the releasable connection between the latch and the spring.

13. A butt pressure contact circuit breaker including a movable butt contact, a stationary contact, a handle, and a circuit responsive latch, and a single bowed leaf spring for butt pressing the movable contact against the stationary contact when the parts are in circuit closed position, and for biasing the movable contact away from the stationary contact in the event of a release by the latch, and for producing a snap movement of the movable contact into circuit closing position following movement of the handle out of circuit open position, the spring having an end connected to the handle and an end connected to the latch, there being a pivotally mounted arm in the breaker to which the latch connection end of the spring is connected and to which the latch is releasably connected, both connections to the arm being adjacent, such arm providing the releasable connection between the latch and the spring.

14. A butt pressure contact circuit breaker including a movable butt contact, a stationary contact, a handle, and a circuit responsive latch, and a single spring for butt pressing the movable contact against the stationary contact when the parts are in circuit closed positions, and for biasing the movable contact away from the stationary contact in the event of a release

75 by the latch, and for producing a snap movement of the movable contact into circuit closing position following movement of the handle, out of circuit open position, the spring being a bowed leaf spring having an end connected to the handle and an end connected to the latch, and on which the movable contact is supported, there being a pivotally mounted arm in the breaker to which the latch connection end of the spring is connected and to which the latch is releasably connected, both connections to the arm being adjacent, such arm providing the releasable connection between the latch and the spring.

15. A circuit breaker including a stationary contact, a bowed leaf spring means, a movable contact operatively connected thereto so as to be moved thereby, a handle directly connected thereto so as to provide for manipulation thereof, a circuit responsive latch directly connected to said spring means, the handle and the latch providing separate direct acting holding means for the spring means, the relation between the spring means, the latch, and the handle being such that on release of the latch the spring means moves around the handle connection thereto as a pivot without requiring movement of the handle so as to bias the contact to open circuit position, and on movement of the handle the spring means moves around the latch connection thereto as a pivot without moving the latch, so as to bias the contact to open circuit position, the points of connection between the handle and spring means and between the latch and spring means being spaced from each other, the movable contact 30 connected to the spring means being formed to butt against the stationary contact, with the spring means biasing the movable contact against the stationary contact when the circuit is closed and the handle and latch hold the spring means, there being a pivotally mounted arm in the breaker to which the latch connection end of the spring is connected and to which the latch is releasably connected, both connections to the arm being adjacent, such arm providing the releasable 35 connection between the latch and the spring.

16. A circuit breaker including a stationary contact, a spring means, a movable contact operatively connected thereto so as to be moved thereby, a handle directly connected thereto so as to provide for manipulation thereof, a circuit responsive latch directly connected to said spring means, the handle and the latch providing separate direct acting holding means for the spring means, the relation between the spring means, the latch, and the handle being such that on release 50 of the latch the spring means moves around the handle connection thereto as a pivot without requiring movement of the handle so as to bias the contact to open circuit position, and on movement of the handle the spring means moves around the latch connection thereto as a pivot without moving the latch, so as to bias the contact to open circuit position, the points of connection between the handle and spring means and between the latch and spring means being spaced from each other, the movable contact 55 connected to the spring means being formed to butt against the stationary contact, with the spring means biasing the movable contact against the stationary contact when the circuit is closed and the handle and latch hold the spring means, the spring being a bowed leaf spring having its ends connected to the handle and latch respectively, there being a pivotally mounted arm in the breaker to which the latch connection end of

the spring is connected and to which the latch is releasably connected, both connections to the arm being adjacent, such arm providing the releasable connection between the latch and the spring.

17. In a circuit breaker controlling mechanism, a stationary contact, a movable contact arranged to butt against the stationary contact, a bowed leaf spring means operatively connected to the movable contact and arranged to bias it against the stationary contact when the spring means is in normal stressed position, a circuit responsive latch directly connected to the spring means for holding it under stress in normal contact biasing position, a rotatably mounted handle directly connected to the spring means and manipulable by rotary movement out of its normal position to stress the spring means and move it bodily out of its normal position and towards the center of rotation of the handle so that when the handle is released after such movement the spring means will tend to relieve itself of its stress with a snap action, the relative arrangement of the parts being such that on such stress relieving movement of the spring means following such handle movement and subsequent release, the spring means will move bodily beyond the center of rotation of the handle and about the connection between the spring means and latch as a pivot, to move the movable contact away from the stationary contact, and also being such that on release of the latch, when the handle and spring means are in normal position, the spring means will tend to relieve itself of its stress with a snap action and in so doing will move bodily about its connection to the handle as a pivot and move the movable contact away from the stationary contact, there being a pivotally mounted arm in the breaker to which the latch connection end of the spring is connected and to which the latch is releasably connected, both connections to the arm being adjacent, such arm providing the releasable connection between the latch and the spring.

18. In a circuit breaker controlling mechanism, a stationary contact, a movable contact arranged to butt against the stationary contact, a spring means operatively connected to the movable contacts and arranged to bias it against the stationary contact when the spring means is in normal stressed position, a circuit responsive latch directly connected to the spring means for holding it under stress in normal contact biasing position, a rotatably mounted handle directly connected to the spring means and manipulable by rotary movement out of its normal position to stress the spring means and move it bodily out of its normal position and towards the center of rotation of the handle so that when the handle is released after such movement the spring means will tend to relieve itself of its stress with a snap action, the relative arrangement of the parts being such that on such stress relieving movement of the spring means following such handle movement and subsequent release, the spring means will move bodily beyond the center of rotation of the handle and about the connection between the spring means and latch as a pivot, to move the movable contact away from the stationary contact, and also being such that on release of the latch, when the handle and spring means are in normal position, the spring means will tend to relieve itself of its stress with a snap action and in so doing will move bodily about its connection to the handle as a pivot, and move the movable contact away from the stationary contact, the spring being a bowed leaf spring having its ends connected to the handle and latch respectively, there being a pivotally mounted arm in the breaker to which the latch connection end of the spring is connected and to which the latch is releasably connected, both connections to the arm being adjacent, such arm providing the releasable connection between the latch and the spring.
